[57] **CLAIM**

The ornamental design for a mud flap for recreational vehicle, as shown and described.

DESCRIPTION

FIG. 1 is a side, front, perspective view of the mud flap for recreational vehicle as attached to a recreational vehicle, with a portion of the recreational vehicle shown in broken lines;

FIG. 2 is a front view of the mud flap for recreational vehicle;

FIG. 3 is a rear view thereof;

FIG. 4 is a bottom view thereof;

FIG. 5 is a top view thereof;

FIG. 6 is a right side view thereof; and,

FIG. 7 is a left side view thereof.

The broken lines shown all drawing views are for illustrative purposes only and form no part of the claimed design.
